MARTIN ADOLF SCHMIDT, OF LYNDHURST, NEW JERSEY, AND CURT ERNST WUNDERLICH, OF BROOKLYN, NEW YORK.

ERASING DEVICE.

Application filed March 23, 1927. Serial No. 177,735.

This invention relates to a device for removing dirt and pencil marks from paper, linen, and similar material.

At present, dirt spots and pencil marks on drawings, manuscripts etc. are usually erased therefrom by means of a solid cake of india-rubber. This known procedure of rubbing one solid cake of india-rubber back and forth against the dirty surface of an article for the purpose of cleaning same requires considerable time, as only a small area of said surface is covered at a time, often damages the edges of said article, roughens and thins paper, tears holes therein, leaves streaky spots, and erases, on pencil-drawings for instance, pencil marks which one does not wish to remove.

Among the objects of our invention are to provide an erasing device adapted to remove light dirt and pencil marks from a drawing or manuscript, and particularly from a comparatively large area thereof at a time, evenly, in very little time, and without doing any damage, and to preserve while cleaning a drawing, particularly a pencil-drawing, heavier marked lines, numerals and other characters thereon which one wishes to retain, and to provide an outfit for handling said erasing material. Another object of our invention is to furnish our erasing device in such a complete make-up that a contact of one's hand with the erasing material or agent as well as with the article from which dirt and light pencil marks are removed, is eliminated.

An important object of our invention is that all parts of same may be manufactured at little cost.

The drawing shows a device in perspective for utilizing said erasing material and a receptacle therefor.

We provide small scrapings or flakes of india-rubber or of similar material adapted to erase dirt spots etc., from paper, linen and the like, which scrapings or flakes may be round, flat or of any other suitable shape, can be produced from remnants of india rubber and are designated rubber flakes henceforth in this document. It is quite likely that similar rubber flakes form a part in other devices, for instance, in an apparatus for graining metallic plates for surface printing, but not for purposes specified and described herein.

The receptacle 1 serves to keep a portion of said rubber-flakes in orderly condition and may be placed in a desk, in a drawer or a drawing-table or elsewhere within easy reach.

The cover 2 of said receptacle furnishes a rubbing plate 3 and has dull edges in order to overcome any resistance and to prevent a tearing or damaging of drawings, manuscripts, etc.

The handle 4 of the cover 2 permits a firm grip.

A strip of felt 5, a brush, or the like, fastened to said cover, serves to quickly gather and to remove the rubber flakes from an article after the cleaning thereof. To clean a dirty drawing, for instance, a quantity of said rubber-flakes is strewn thereon from the receptacle 1 and evenly spread thereupon by means of the rubbing plate 3 of the cover 2. A pressure, and simultaneously a back and forth or circular motion of said cover, keep the rubber-flakes in a rubbing motion and rotation which produce the cleaning effect. After the cleaning process, the rubber-flakes may be removed into the receptacle 1 by means of the brush 5 to be used over and over again.

It is understood that no part of said cover shall get in direct contact with the article undercleaning treatment and that no damage can be done by the rubber-flakes to the article under cleaning treatment, especially to the edges thereof, as said rubber-flakes produce a greater elasticity and yield better than one solid cake of erasing rubber to any obstacle.

Said rubbing plate is of harder material than the rubber-flakes and may be replaced by any means having a suitable rubbing surface. Furthermore, it may be corrugated, flat or differently shaped to obtain a firm hold of the rubber-flakes beneath it and to effect a good service of same.

All changes and modifications which come within the scope and spirit of our invention, are a part of same.

We claim:

- An erasing device for removing dirt and pencil marks, comprising a quantity of "rubber-flakes" of the character described.
- In combination with an erasing device comprising a quantity of "rubber-flakes" of

the character described, a rubbing plate adapted to engage said "rubber-flakes" as and for the purpose herein set forth.

3. An erasing device for removing dirt and pencil marks comprising a quantity of erasing material in finely divided form and of a character to remove the marks by rubbing or friction.

4. An erasing device comprising a quantity of erasing material in finely divided form and of a character capable of removing marks by friction and a rubbing plate for said erasing material. 10
